(57) **CLAIM**

The ornamental design for a drum housing for a juice extractor, as shown and described.

DESCRIPTION

1. Drum housing for a juice extractor

1.1 Perspective view

1.2 : Front view

1.3 : Back view

1.4 : Left view

1.5 : Right view

1.6 : Top view

1.7 : Bottom view

1.8 : Cross-sectional view

1.9 : Reference view

Drawing 1.8 is a cross-sectional view taken along 1.8-1.8 of drawing 1.6. Drawing 1.9 is a reference view showing the state that the claimed design is assembled in a juice extractor, and the broken line showing environment forms no part of the claimed design.
